UNITED STATES PATENT OFFICE.

ORVILLE M. MORSE, OF JACKSON, MICHIGAN, ASSIGNOR TO THE KNICKER-BOCKER COMPANY, OF SAME PLACE.

BOLTING-REEL.

SPECIFICATION forming part of Letters Patent No. 381,023, dated April 10, 1888.

Application filed October 19, 1887. Serial No. 252,772. (No model.)

To all whom it may concern:

Be it known that I, ORVILLE M. MORSE, of Jackson, in the county of Jackson and State of Michigan, have invented new and useful Improvements in Bolting-Reels, of which the following is a specification.

This invention relates to a bolting-reel which is provided with an internal agitator, whereby the material to be bolted is distributed over the bolting-cloth and prevented from moving over the bolting-cloth in a large body, and has for its object to improve the construction of the agitator.

It is well known that in ordinary bolting-reels the material lying upon the lower portion of the reel is elevated on one side of the reel by the rotation thereof until the friction between it and the surface of the reel is overcome, when the entire mass slides back to the lowest portion of the reel. This manner of bolting brings only a small portion of the material in contact with the bolting-surface at a time, whereby the bolting capacity is kept low and the impact of the descending mass against the lower portion of the bottom of the reel is liable to force specks through the bolting-cloth. My internal agitator is designed to overcome these difficulties in a simple and efficient manner and without any violent or beating action, which also tends to force impurities through the bolting-cloth.

My invention consists of the improvements which will be hereinafter fully set forth, and pointed out in the claims.

In the accompanying drawings, consisting of two sheets, Figure 1 is a longitudinal sectional elevation of a bolting-reel provided with my improvements. Fig. 2 is a cross-section of the same. Fig. 3 is a fragmentary elevation of the internal agitator on an enlarged scale. Fig. 4 is a fragmentary cross-section of the same and adjacent parts. Fig. 5 is a cross-section of a reel in which the internal agitator and the reel are rotated with differential speed. Fig. 6 is a fragmentary longitudinal sectional elevation thereof. Fig. 7 is a fragmentary cross-section showing a modified construction of the internal agitator. Fig. 8 is a fragmentary longitudinal section thereof. Figs. 9, 10, 11, and 12 are fragmentary cross-sections of modified constructions of the internal agitator.

Like letters of reference refer to like parts in the several figures.

A represents the frame of the reel; a, the top board of the casing; a', the receiving-hopper underneath the reel, and a² the conveyer.

B B' represent the movable doors or panels which form the side walls of the casing.

c represents the reel-shaft, C the head at the feed end of the reel, and C' the head at the tail end of the reel.

D represents the bolting-cloth, extending from the head C to the head C', and supported by external ribs, d, and rings d'.

E represents a drum secured to the reel-shaft within the reel and turning therewith.

F represents the internal agitator, composed of a wire net and surrounding the drum E. This net may rest directly against the outer surface of the drum E, as represented in Figs. 1, 2, and 4, or it may be supported at a distance from the outer surface of the drum by rings e and standards e', as represented in Figs. 7 and 8, or it may be supported by rings e², resting against the edges of a polygonal drum, as represented in Figs. 9, 10, and 11, or it may be applied in sections to the drum, as represented in Fig. 12, instead of enveloping the entire drum.

The agitator-net is preferably composed of spiral wires extending lengthwise of the reel and the drum and intertwined or interlocked with each other, as represented in Fig. 3. The interlocked spiral wires form alternate ridges and depressions which extend spirally around the drum, as indicated by the arrows in Fig. 3. These spiral ridges propel the material toward the tail end of the reel and enable the latter to be arranged horizontally.

In the construction of the machine represented in Figs. 1, 2, 4, 7, 8, 9, 10, 11, and 12 the agitator-net is arranged at a distance from the inner surface of the bolting-cloth, so as to leave a free space between the agitator and the bolting-cloth, the former touching no part of the bolting-cloth. In this construction of the machine the agitator serves to break up the mass of the material to be bolted, so as to prevent considerable accumulations from being formed, and causes the material to be turned over frequently in passing over the bolting-surface. It also serves to elevate the material on the ascending side of the reel and to distribute it

over the larger portion of the reel-surface on the ascending side thereof, and its action is so gentle that no impurities are forced by it through the bolting-cloth.

- 5 When the agitator-net is supported at a distance from the surface of the drum, as represented in Figs. 7 and 8, or at a distance from portions of the surface of the drum, as represented in Figs. 9, 10, and 11, the free space or spaces formed between the agitator and the drum cause the material to pass repeatedly through the agitator toward and from the drum, whereby the disintegrating action of the agitator is increased.
- 15 In the construction of the machine represented in Figs. 5 and 6 the drum E', which supports the agitating-net, and the reel are rotated with differential speed by means of separate driving-pulleys g'g', or by other suitable means. In this construction the agitating-net hangs loosely on the drum and touches the lower portion of the bolting-cloth, as represented in Fig. 5. As the drum and the reel rotate with differential speed, the line of contact of the agitator with the net changes continually, and the agitator has in this case the additional function of keeping the meshes of the bolting-cloth clear.

I claim as my invention—

1. The combination, with a bolting-reel, of a 30 rotating support arranged within the reel, and a cylindrical agitator-net mounted upon said support, substantially as set forth.
2. The combination, with a bolting-reel, of a 35 rotating support arranged within the reel, and an internal agitator composed of intertwined spiral wires mounted upon said support, substantially as set forth.
3. The combination, with a bolting-reel, of a 40 drum arranged within the reel, and an agitator-net mounted upon said drum, substantially as set forth.
4. The combination, with a bolting-reel, of a 45 drum arranged within the reel, supports attached to the drum and projecting beyond the surface thereof, and an agitator-net resting upon said supports, substantially as set forth.

Witness my hand this 15th day of October, 1887.

ORVILLE M. MORSE.
